UNITED STATES PATENT OFFICE.

PETER J. KLEIN, OF NEW YORK, N. Y.

RAILWAY-SPIKE.

SPECIFICATION forming part of Letters Patent No. 643,658, dated February 20, 1900.

Application filed May 25, 1899. Serial No. 718,246. (No model.)

To all whom it may concern:

Be it known that I, PETER J. KLEIN, a citizen of the United States, residing at New York, (Jamaica,) in the county of Queens and State 5 of New York, have invented a new and useful Railway-Spike, of which the following is a specification.

This invention relates to spikes; and the object thereof is to provide a spike by means of 10 which a wooden rail may be secured to a tie or sleeper without passing the spike through the same, so that the spike may be disengaged without injury to the rail.

My invention is especially adapted for use 15 in electric-railway systems where the current is taken from a "third rail." It has been the custom to make this third rail of iron or steel; but lately an attempt has been made to use a wooden rail with an iron or steel plate on the 20 top thereof and wires mounted in a groove in the top of the rail beneath the plate. A serious objection to the use of this system has arisen from the fact that in order to secure the wooden rail in position the spikes had to 25 be driven through the same into the tie or sleeper, and in repairing the road when it was necessary to remove the tie or sleeper the spikes had to be withdrawn, and as the rails are comparatively very fragile they are generally so injured by this operation that the 30 entire rail or section of rail has to be replaced. I have accordingly designed this spike to hold the rail in position without driving it through the rail. I attain this object by the device 35 illustrated in the accompanying drawings, in which—

Figure 1 is a sectional end view of a third rail constructed of wood in accordance with the present practice and showing one of my 40 improved spikes applied thereto and a second spike in the position it occupies when being driven into the sleeper, and Fig. 2 is a perspective view of my improved spike.

Similar numerals of reference refer to like 45 parts in each of the views.

In the practice of my invention I provide a spike consisting of two parts 5 and 6, each of which is provided at one end with a lug 7, whereby a shoulder 8 is formed on each, and 50 through a hole in each of said lugs I pass a bolt 9, by means of which they are held to-

gether and a hinged joint is formed. The part 5 is provided with a beveled end 10 and the part 6 is provided with an angular extension 11, which is provided with a beveled end 55 12, the beveled part 12 being on the sides when the spike is in the position shown in Fig. 1.

In operation the spike is driven into the sleeper 13, the spike being in the position 60 shown at the left of Fig. 1 and the sledge being applied as indicated by the arrow 14. When driven into the said sleeper as far as desired, the part 6 is then turned up until the beveled end 12 of the extension 11 is against 65 the rail, when by applying the sledge, as indicated by the arrow 15, the same is driven into the said rail, and when all the spikes are in position the said rail will be securely held, as will be readily understood. When it is de- 70 sired to remove a tie or sleeper, a bar can be inserted between the part 6 and the rail 16 and the part 6 can be thrown back into the position shown at the left of Fig. 1, when the spike can be easily withdrawn from the 75 sleeper, as will be readily understood, without injury to the rail.

It will be noticed that the part 11 has beveled sides, so that in driving it into the rail 16 the grain of the wood is cut instead of 80 being forced apart, as would be the case if the top and bottom of the part 11 were beveled or if the part 11 were pointed.

Instead of driving the spike into the sleeper when in the position shown at the left of Fig. 1 85 the spike may be held upright, as in Fig. 2, and I have so constructed the lugs 7 and shoulders 8 that they will bear against each other, respectively, when being driven, so that the bolt 9 will not be broken. It is also evident 90 that if the holes in the lugs 7 were made large enough so that the bolt would have some play the stress would come entirely on the lugs and shoulders if the spike were driven when standing upright.

I do not limit myself to the kind of joint which may be formed between the parts 5 and 6 nor to the angle at which the extension 11 projects from the body of the part 6, but reserve the right to make all changes 100 which fairly come within the scope of my invention.

Having thus described my invention, what I claim, and desire to secure by Letters Patent, is—

1. A railway-spike consisting of two parts 5 hinged together, one of said parts being adapted to be driven into the tie or sleeper, and the other part being adapted to be driven into the rail, for the purpose set forth.
2. A railway-spike consisting of two parts 10 hinged together, one of said parts being sharpened at the free end, the other part being provided with an angular extension which is sharpened at the end, for the purpose set forth.
3. A railway-spike consisting of two parts 15 hinged together, one of said parts being sharpened at the free end, and the other part being provided with an angular extension the end of which is beveled at the sides, substantially 20 as and for the purpose set forth.

4. The herein-described railway-spike, consisting of parts 5 and 6, said part 5 being sharpened at the free end, and being provided with a lug 7 and shoulder 8, the part 6 being provided with a similar lug and shoulder, and 25 said lugs being connected together in such a way that the end of each lug will bear against the shoulder of the opposite part when the said parts are extended, said part 6 being provided with an angular extension 11 the 30 sides of the end of which are beveled, substantially as and for the purpose set forth.

In testimony that I claim the above I have hereto affixed my signature in the presence of two subscribing witnesses.

PETER J. KLEIN.
